UNITED STATES PATENT OFFICE.

HAMNER J. CORDLE, OF LITTLETON, NORTH CAROLINA.

CARBURETER.

1,205,859.

Specification of Letters Patent. Patented Nov. 21, 1916.

Application filed March 16, 1916. Serial No. 84,619.

To all whom it may concern:

Be it known that I, HAMNER J. CORDLE, a citizen of the United States, residing at Littleton, in the county of Halifax and State 5 of North Carolina, have invented certain new and useful Improvements in Carbureters, of which the following is a specification.

My invention relates to improvements in carbureters, for use in connection with 10 internal combustion engines, having one or more cylinders.

An important object of the invention is to provide a carbureter of the above mentioned character, formed of few and simple parts 15 and adapted to effect an intimate mixture between the air and liquid fuel.

A further object of the invention is to provide means for automatically increasing the supply of carbureted air to the engine, 20 as the suction therefrom increases, due to the increased speed of the engine.

Other objects and advantages of the invention will be apparent during the course 25 of the following description.

In the accompanying drawings forming a part of this specification and in which like numerals are employed to designate like parts throughout the same, Figure 1 is a 30 central vertical longitudinal sectional view through a carbureter embodying the invention, and, Fig. 2 is a horizontal sectional view taken on line 2—2 of Fig. 1.

In the drawings, wherein for the purpose of illustration is shown a preferred embodiment of my invention, the numeral 5 designates a casing or chamber, which is preferably circular in horizontal cross-section, and constitutes the body portion of the carbureter. Formed upon one side of the casing 35 5 is a liquid fuel circulating pipe 6, one end of which may be connected with a pump (not shown) and the other end of which may be connected with a tank or other receptacle holding the liquid fuel, and from 40 which the pump withdraws the same. It is thus apparent that the pipe 6 is included in a liquid fuel circulating system. Having communication with the pipe 6 is a depending pipe 7, having a lower horizontal portion 8 projecting into the casing 5, adjacent its bottom, as shown. Formed upon the 45 opposite side of the casing 5 is an air supply pipe 9, communicating with the atmosphere, and having a valve 10 arranged therein, as shown. The casing 5 is preferably provided 50 with an annular interior horizontal flange 11.

The horizontal portion 8 of the pipe 7 is provided at its inner end with a screw-threaded opening 12, receiving the externally screw-threaded end of a valve casing 13. This lower end of the valve casing 13 is formed solid, as shown at 14, and above this solid portion is the longitudinal bore 15 or opening of the valve casing. Formed through the solid portion 14 is a port 16, 55 having tapered ends 17 and 18. The passage of the liquid fuel through the port 16 may be controlled by a needle-valve 19, having its tapered end projecting into a tapered portion 17, and having screw-threaded engagement with the bottom of the casing 5, as shown at 20, and projecting outwardly beyond the same, as shown.

The valve casing 13 is normally more or less vertically arranged and is provided at 60 its upper end with a more or less horizontal tray 21, having radially disposed grooves 22, formed upon its upper surface. Adapted to be arranged upon and contact with the upper surface of the tray 21 is a more or less horizontal cap 23, having a needle-valve 24 rigidly connected therewith and depending therefrom. This needle-valve extends longitudinally within the valve casing 13 and its tapered end is adapted to enter the portion 18 of the port 16, to cover and uncover the same. The numeral 25 designates a 65 guide ring, rigidly mounted upon the needle-valve 24, and adapted to contact with a stop element 26, to positively limit the upward movement of the needle-valve. The ring 25 is provided with apertures 27, to 70 permit of the free passage of the liquid fuel through the valve casing 13. Depending from the cap 23 and rigidly connected therewith is a guide sleeve 28, operating within the upper end of the valve casing 13, thus retaining the needle-valve in its proper position. The guide sleeve 28 is provided 75 near its upper end with a horizontal set of openings or apertures 29, which are covered when the cap 23 is in the lower position but have registration with the grooves 22 when the cap is moved to the uppermost position.

The upper end of the casing 5 is provided 80 with an outlet conduit 30, having connection with a coupling 31, adapted to be secured to a pipe connected with the manifold pipes of the engine. A valve 32 is arranged within the coupling 31, as shown.

Mounted to reciprocate within the conduit 85 30 is a tubular air supply valve 33, provided

110

- with elongated slots 34, receiving the inner ends of stop bolts or elements 35. At its lower end the tubular valve is provided with an interior annular flange 36, as shown.
- 5 When the tubular valve 33 is in the lowermost position there is an air passage between it and the cap 23. The upward movement of the tubular valve is opposed by a spring 37, as shown.
- 10 In the operation of the apparatus, the pipe 7 is maintained filled with the liquid fuel, such as gasolene, by the same being continuously circulated in the pipe 6. The needle valve 19 may be adjusted to regulate 15 the permanent passage of the liquid fuel through the port 16. The cap 23 and valve 24 are gravity operated, and automatically return to the lowermost position, the valve 24 then covering or closing the port 16.
- 20 Upon the down stroke of the piston in each cylinder of the engine, the vacuum created therein is transmitted to the casing 5, and elevates the cap 23 and needle 24. This movement of the cap 23 brings the apertures 25 29 into registration with the grooves 22, whereby the gasolene will pass outwardly through these grooves and be sprayed or discharged into the incoming air, being drawn through the casing 5. In this manner the air is thoroughly carbureted before 30 passing to the cylinders of the engine. When the speed of the engine increases, the suction is correspondingly increased in the casing 5. This increased suction serves 35 to move the tubular valve 33 upwardly, in opposition to the spring 37, whereby the passage between the valve 36 and cap 23 is increased. By this means additional air will be drawn into the casing 5, carbureted, and 40 carried to the cylinders.
- It is to be understood that the form of my invention herewith shown and described is to be taken as a preferred example of the same, and that various changes in the shape, 45 size, and arrangement of parts may be resorted to without departing from the spirit of the invention or the scope of the subjoined claims.

Copies of this patent may be obtained for five cents each, by addressing the "Commissioner of Patents, Washington, D. C."

Having thus described the invention, I claim:

1. In a carbureter of the character described, a casing having a liquid fuel supply device and an air supply device, a substantially vertical valve casing arranged within the said casing and having its lower end provided with a port in communication with the interior of the liquid fuel supply device, a tray carried by the upper end of the valve casing and having grooves extending to the interior thereof, a cap arranged near and above the tray, a needle-valve depending from the cap to be moved thereby and adapted to cover and uncover the port, a sleeve attached to the cap and depending therefrom into the valve casing and having apertures adapted to be moved into and out of registration with the grooves, and an outlet device for the casing arranged near and above the cap. 50
2. In a carbureter of the character described, a casing having a liquid fuel supply conduit leading into the lower end thereof, a substantially vertical valve casing connected with the conduit and having its lower end provided with a port in communication 55 with the conduit, a manually operated valve to cover and uncover the lower end of the port, a tray carried by the upper end of the valve casing and having grooves extending to the interior thereof, a cap arranged near and above the tray, a needle-valve connected 60 with the cap and depending therefrom and adapted to cover and uncover the upper end of the port, a sleeve connected with the cap and depending therefrom into the valve 65 casing and having apertures adapted to be moved into and out of registration with the grooves, an outlet conduit connected with the casing near and above the cap, a suction 70 operated air control valve mounted in the outlet conduit, and a spring to oppose the opening movement of the suction operated valve. 75
